UNITED STATES PATENT OFFICE

WILLIAM A. GOTTL, OF MELROSE, MASSACHUSETTS, ASSIGNOR TO JENNEY MANUFACTURING COMPANY, OF BOSTON, MASSACHUSETTS, A CORPORATION OF MASSACHUSETTS

DESIGN FOR A PUMP CASING FOR SERVICE STATIONS

Application filed February 13, 1932. Serial No. 42,851. Term of patent 14 years.

To all whom it may concern:

Be it known that I, WILLIAM A. GOTTL, a citizen of the United States, residing at Melrose, Middlesex County, State of Massachusetts, have invented a new, original, and ornamental Design for a Pump Casing for Service Stations, of which the following is a specification, reference being had to the accompanying drawings, forming part thereof.

In the drawings,

Figure 1 is a perspective view of a casing showing my new design;

Fig. 2 is a front elevation on a reduced scale of the casing shown in Fig. 1; and

Fig. 3 is an end view on a reduced scale of said casing.

I claim:

The ornamental design for a pump casing for service stations, substantially as shown.

WILLIAM A. GOTTL.
